SPOON OR SIMILAR ARTICLE

Kae E. Jones, New York, N.Y., assignor to Welling Ware,
Inc., New York, N.Y., a corporation of New York

Application November 10, 1958, Serial No. 53,333

Term of patent 7 years

(Cl. D54—12)

Fig. 1 is a front view of a spoon or similar article, showing my new design.

Fig. 2 is a side elevational view thereof.

Fig. 3 is a back view thereof.

Fig. 4 is an enlarged fragmentary view showing the ornamental detail near the top of the handle, as shown in Fig. 3.

Fig. 5 is an enlarged fragmentary view showing the ornamental detail near the top of the handle, as shown in Fig. 3.

Figs. 6 and 7 are enlarged cross-sectional views taken respectively on lines 6—6 and 7—7 of Fig. 1.

The essential features of my design for spoon or similar article reside in the configuration of the handle in com-

bination with the particular type of ornamentation as applied thereto.

I claim:

The ornamental design for a spoon or similar article, substantially as shown and described.
